[57] **CLAIM**

The ornamental design for a combined lockable bracelet and key therefor, as shown and described.

DESCRIPTION

FIG. 1 is a perspective view of a combined lockable bracelet and key therefor showing my new design; FIG. 2 is a perspective view of the bracelet with key removed;

FIG. 3 is a front elevational view thereof; the rear being identical;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view of the key, the rear being identical;

FIG. 9 is a left side elevational view thereof, the right side being identical;

FIG. 10 is a top plan view thereof;

FIG. 11 is a bottom plan view thereof.
